United States Patent Office

Des. 229,053
Patented Nov. 6, 1973

229,053

SEPTIC TANK

Paul Le Blanc, 160 Vero Beach Blvd.,
Weston, Ontario, Canada

Filed Feb. 11, 1972, Ser. No. 225,689

Term of patent 14 years

Int. Cl. D23—01

U.S. Cl. D23—2

FIG. 1

FIG. 2

FIG. 1 is a perspective view taken from the top, one end and side of a septic tank embodying my new design; and

FIG. 2 is a perspective view taken from the bottom, side and end opposite that shown in FIG. 1.

I claim:

The ornamental design for a septic tank, as shown.
